(57) **CLAIM**

The ornamental design for a digital video disc player, as shown and described.

DESCRIPTION

FIG. 1 is a front, top and right side perspective view of a digital video disc player showing our new design;
FIG. 2 is a front elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a rear elevational view thereof.
FIG. 8 is a rear, top and left side perspective view thereof with the cover in the open position; and,
FIG. 9 is a reduced front, top and right side perspective view thereof combined with a portable LCD monitor.
The broken lines showing environmental structure are for illustrative purposes only, and form no part of the claimed design.
